US00D628776S

(12) **United States Design Patent**
Cofinco

(10) **Patent No.:** **US D628,776 S**
(45) **Date of Patent:** **** Dec. 14, 2010**

(54) **SHOE**

D291,501 S 8/1987 Tong
D322,881 S 1/1992 Bushman

(75) Inventor: **Ricardo Cofinco**, Los Angeles, CA (US)

(73) Assignee: **Kommonwealth, Inc.**, West Hollywood, CA (US)

(Continued)

(**) Term: **14 Years**

Primary Examiner—Dominic Simone
(74) *Attorney, Agent, or Firm*—Baker & McKenzie LLP

(21) Appl. No.: **29/316,304**

CLAIM

(22) Filed: **Sep. 11, 2009**

The ornamental design for a shoe, as shown and described.

(51) **LOC (9) Cl.** **02-04**

DESCRIPTION

(52) **U.S. Cl.** **D2/908**
